UNITED STATES PATENT OFFICE.

DAVID R. GILL, OF ERIE, PENNSYLVANIA, ASSIGNOR OF ONE-HALF TO HAROLD M. STURGEON, OF ERIE, PENNSYLVANIA.

FORGING PRESS.

Application filed November 28, 1921. Serial No. 518,291.

To all whom it may concern:

Be it known that I, DAVID R. GILL, a citizen of the United States, residing at Erie, in the county of Erie and State of Pennsylvania, have invented certain new and useful Improvements in Forging Presses; and I do hereby declare the following to be a full, clear, and exact description of the invention, such as will enable others skilled in the art 10 to which it appertains to make and use the same, reference being had to the accompanying drawings, and to the letters of reference marked thereon, forming part of this specification.

15 My invention relates to forging presses, and particularly to that type of forging press adapted to reduce the diameter of billets or other cylindrical bodies.

The object of my invention is to provide 20 a forging mechanism which will exert a continuous pressure on the work-piece, which pressure will travel in a combined circumferential and longitudinal direction along a portion of the work-piece as it passes through 25 the mechanism.

In carrying out the objects of my invention I provide a plurality of rotatable members which are mounted in pairs in the machine, the units of each pair of rotatable 30 members being rotatable on axes diametrically offset from the axis of the pass; each unit of a pair of rotatable members having secured thereon a forging-die having a face of volute-spiral form, i. e., one end of said 35 face being out of the plane of the other end, and the radius thereof progressively decreasing from the larger end of the smaller end thereof, the axis of each die being the axis of the pair of rotatable members to 40 which it is secured, and the said dies being interjacent of each other.

This arrangement of mechanism causes the volute-spiral dies to grasp the work-piece 45 between their opposing ends and cause said work-piece to rotate in unison with said dies while the diametric points of contact between said dies and the work-piece moves circumferentially and longitudinally towards the opposite ends of said dies, the pressure exerted by the dies upon the work-piece being regulated by the longitudinal feeding of 50 the work-piece with relation to the volute-spiral forging surfaces of the dies.

The volute-spiral forging surfaces of the dies are substantially one turn around a 55 circle in length, so that at each complete revolution of the dies one end of the volute-spiral forging surfaces thereof releases the work-piece and the other end thereof grasps 60 the same.

In my invention there is no rolling action between the dies and work-piece, but on the contrary the dies and work-piece rotate in unison; the dies squeezing the work-piece continuously between them, opposite to the 65 axis of each die, thus producing a continuous forging operation on the work-piece during the rotation of the mechanism, which gradually reduces the diameter of the work-piece by forcing the metal thereof in the direction 70 of the travel of the squeezing operation of the dies on the work-piece.

These and other features of my invention will appear hereinafter and are illustrated in the accompanying drawings in which:

Figure 1, is a plan view of my improved 75 rotary forging press.

Figure 2, is a vertical section of the same on the line 2—2 in Fig. 1.

Figure 3, is a plan view of the volute-spiral forging dies of my mechanism with a work-piece grasped between them in the position thereof indicated by broken lines in Fig. 1.

Figure 4, is an end elevation thereof.

Figure 5, is a side elevation of the volute-spiral dies in the position thereof indicated in section in Fig. 2, said dies grasping the small end of a work-piece.

Figure 6, is a like view of the same after 90 one complete revolution thereof, showing the same grasping the larger diameter of the work-piece.

Figure 7, is a side elevation of one of the dies looking into the open side thereof.

Figure 8, is a vertical section of the volute-spiral dies and hollow work-piece, with a mandrel therein for forming said billet into a tube.

Figure 9, is a like view of the volute-spiral 100 dies and hollow work-piece with a tapered mandrel for reducing the external and internal diameter thereof.

In these drawings (see Figs. 1 and 2) A indicates the base of the machine upon which 105 is secured upright bracket supports A'A'.

Upon the adjacent faces of the bracket-supports A', I secure bearing members B B, upon which are rotatably mounted gear wheels B' B², and rotatable rings b' b², the axis of the gear wheel B' and ring b' being on the line b³, and the axis of the wheel B² and ring b² being on the line b⁴ (see Fig. 2) said axes being diametrically offset from the center line of the pass as shown in said figure.

10 The wheels B' and B² and the rings b' and b² are preferably mounted at identical angles to the center line of the pass as indicated in Fig. 1, for the purpose hereinafter set forth. These wheels and rings are provided with 15 anti-friction roller bearings C for the purpose of eliminating friction.

10 The bearing members B, B, are preferably inset into the upright bracket supports A' and are secured in place by means of tap-bolts C' and the rings b' and b² and their roller bearings are secured on the bearing members B by means of dies D D, which are secured in place thereon by means of tap-bolts d. The brackets A', bearing members 25 B, and dies D at each end of the machine are provided with an opening on the center line of the pass as indicated by broken lines in Fig. 1, and full lines in Fig. 2, through which the work-piece passes.

30 Secured to the wheel B' at diametrically opposite points are plates E E, which extend laterally therefrom over the ring b² and are bolted or otherwise secured to the ring b' at the opposite end of the machine. Secured to the wheel B² at diametrically opposite points are the plates E' E' which extend over the ring b' to and are secured to the ring b² between the plates E, so that when the wheels B' and B² are rotated, the 35 plates E E and E' E' and the rings b' and b² revolve around their respective axes b³ and b⁴ in unison.

Secured between the plates E E is a forging die F which is of square exterior form as 45 shown in Fig. 4, and is provided with an interior forging face of volute-spiral form—i. e. said forging face is curved, the radius of said curve being progressively shortened from one end of said forging face to the other, so that the pass through said die, as seen from one end to the other, is tapering or volute in form. Secured between the plates E' E' is a duplicate forging die F', thus supporting the die F' upon the axis b³ of the wheel and ring B² b²; the two dies F and F' being thus supported interjacent to each other.

50 Referring to Fig. 7, the end thereon indicated by the reference letter f has a shorter radius than the end f', the radii of the volute-spiral forging surface f² gradually increasing in length from the end f thereof to the end f' so that the volute-spiral pass through said dies F and F', looking at the 55 ends thereof having the largest radius, is

tapered or conical to correspond with the taper produced on that portion of the work-piece being operated upon.

In Figs. 8 and 9 is shown means for adapting the machine heretofore described to 70 forging the walls of a pierced billet or tube H, which consists in providing a mandrel G (see Fig. 8) within the forging dies F and F' against which said dies forge the metal of the tube.

75 This mandrel is shown of uniform diameter and the stem g thereof extends back out of the pass of the machine and rests in an open bearing in the top of a pedestal g', which is adapted to support the same vertically and resist the longitudinal feeding strain exerted thereon by the machine as the billet or tube H is being drawn into the machine by the diagonal volute-spiral forging dies F and F'; said tube or billet being thereby forced to travel longitudinally with 80 relation to said dies and mandrel; said mandrel remaining stationary and in position to resist the forging strain of said dies just as an anvil does with relation to the hammer of a forging press.

85 The mandrel G and stem g is free to rotate in unison with the billet H and dies F and F' during the operation of the machine, and is provided with a flange g² on the rear end thereof, which, by engagement with the pedestal g' prevents the longitudinal movement of the mandrel, while leaving it free to rotate therewith. This mandrel G being of uniform diameter is suitable for reducing 90 the outside diameter of billets or tubes.

95 In Fig. 9 I show a tapered mandrel G' in opposition to the forging dies F and F', which is adapted to enable the machine to 100 reduce the internal diameter as well as the outside diameter of the tube or billet H. In order to control the thickness of the wall of the finished tube I have provided a pedestal J in the upper end of which is mounted a slide J' which is provided with an adjusting screw j having a hand-wheel j' by means of which the slide J' can be moved toward or from the forging dies in the machine. This slide is provided with an open-journal bearing adapted to receive the mandrel stem g and against which the flange g² operates as 110 in Fig. 8.

115 It is obvious that if the mandrel G' is drawn backward, the forging dies will leave the tube wall thicker than if the mandrel is allowed to move further forward through the dies, so that by means of a tapered mandrel I can reduce the internal and external diameters of a billet or tube H, as well as regulate the thickness of the walls of the 120 finished tube.

125 In operation a properly heated billet is introduced into the pass of the machine and is grasped by the forging dies, which press the billet from diametrically opposite sides,

owing to the offset axes of revolution of said dies, the grip of said dies upon the billet travelling backward from the initial point of engagement to the ends f' of said dies and then the ends f of said dies again grasping the billet and the forging pressure again repeated.

During this travel of the gripping point longitudinally, it retains a constant transverse relation with the billet corresponding with the offset axes of rotation of the dies, and the grip being constant, the billet must of necessity revolve in unison with the forging dies, so that said dies can only exert a forging pressure and the metal of the billet is forced backward by being squeezed between the dies, instead of by a rolling relation between the dies and billet.

It will also be evident to those skilled in the art that, the axis of rotation of the die F being at an angle to the axis of rotation of the die F' , they will, by their action upon the billet, steadily draw the billet and cause it to travel longitudinally through the machine.

Having thus fully shown and described my invention so as to enable others to utilize the same, I do not desire to limit myself to the exact mechanism shown and described, as many modifications can be made therein without departing from the scope of my invention; therefore what I claim as new and desire to secure by Letters Patent is:—

35 1. In a machine of the class described, a plurality of forging dies each having forging surfaces encircling the axis of the pass, one end of said forging surface being out of the plane of the other end thereof and the radius thereof progressively decreasing from the entrance end of the exit end thereof, said dies being interjacent of each other and forming a conically shaped pass therethrough, and mechanism adapted to support said dies and rotate each die around an axis offset from the axis of the other die.

50 2. In a machine of the class described, a pair of duplicate forging dies each having a forging surface encircling the axis of the pass and arranged interjacent of each other, one end of said forging surface being out of the plane of the other end thereof and the radius thereof progressively decreasing from the entrance end of the exit end thereof, said forging surfaces forming a conically shaped pass through said dies, and mechanism adapted to support said dies and rotate each die around an axis offset from and at an angle to the axis of the other die.

55 3. In a machine of the class described, a forging die having an internal forging surface, one end of said surface being out of the plane of the other end, the radius of said surface progressively decreasing from

the entrance end of said die to the exit end thereof.

4. In a machine of the class described, a forging die having an internal forging surface extending once around the axis thereof, and having one end thereof out of the plane of the other end, the radius of said surface progressively decreasing from the entrance end to the exit end thereof. 70

5. In a machine of the class described, a forging die having an internal forging surface the radius of which progressively decreases from the entrance end to the exit end and having one end thereof out of the plane of the other end, and means to support and revolve said die around its axis. 80

6. In a machine of the class described, a forging die having an internal forging surface, and means to support the same from opposite sides and cause it to revolve around its axis. 85

7. In a machine of the class described, a pair of spaced bearing blocks, rotatable members on each of said blocks, a pair of plates secured to each of said rotatable members at diametrically opposite sides thereof so as to bridge the space between said rotatable members, a forging die having an internal forging surface secured to said plates at opposite sides of said die, 90 and means to cause said rotatable members and plates to revolve. 95

8. In a machine of the class described, a pair of spaced rotatable members adapted to revolve on a common stationary axis, a pair of bridge plates secured on said rotatable members at diametrically opposite sides thereof, and integrally connecting them in a single unit, and mechanism to rotate said unit. 100 105

9. In a machine of the class described, a pair of interlaced rotatable frames mounted on stationary bearings, a forging die secured in each frame the dies being arranged interjacent of each other, and mechanism to cause said frames to rotate. 110

10. In a machine of the class described, a plurality of pairs of spaced stationary journal-bearings each pair having a common axis, rotatable members mounted on said bearings, and plates bridging the space between the rotating members on each spaced pair of bearings and secured thereto so that said pairs of spaced members and said plates form complete integral units inter- 115 120 jacent of each other.

11. In a machine of the class described, a pair of spaced stationary journal bearings having a common axis, rotatable members mounted upon said bearings, plates bridging the space between said members and uniting said members as an integral rotatable unit, another pair of journal bearings on a common axis offset from the common axis of the first named journal bearings, 125 130

- duplicates of the first mentioned rotatable members mounted on the last mentioned journal bearings, plates bridging the space between the last mentioned rotatable members and uniting them into integral rotatable units, the said first and last mentioned bridge plates alternating with and being interjacent of each other, and mechanism to rotate said rotatable units.
- 10 12. In a machine of the class described, a base frame, upright end frames on said base frame, a pair of journal bearings secured on each upright end frame, one of each pair of said journal bearings on one end frame 15 having a common axis with an alternate journal bearing on the other end frame and offset from the axis of the other journal bearings, rotatable members mounted on said journal bearings, plates secured to and 20 bridging the space between the rotatable members mounted on said journal bearings

having identical common axes, a forging die secured between each pair of said bridge plates and arranged interjacent of each other, and mechanism to rotate said rotatable mechanism. 25

13. In a machine of the class described, a wheel rotatably mounted at each end of the machine upon axes offset from each other, and a ring rotatably mounted adjacent to 30 the inner face of each of said wheels upon axes common with the wheel at the opposite end of the machine, bridge plates integrally uniting each of said rings with the wheel on the axis of said ring, a forging die secured between each pair of bridge plates and arranged to operate in opposition to each other, and mechanism to rotate said wheels. 35

In testimony whereof I affix my signature. 40

DAVID R. GILL.
